UNITED STATES PATENT OFFICE.

LESTER A. GRIMES, OF MONTCLAIR, NEW JERSEY, ASSIGNOR TO GRIMES SPRINKLER COMPANY, INC., OF NEWARK, NEW JERSEY, A CORPORATION OF NEW JERSEY.

ALARM CHECK VALVE.

Application filed July 17, 1925. Serial No. 44,221.

The present invention relates to alarm valves for automatic sprinkler systems. Such devices broadly comprise a casing having therein a normally closed check valve in the path of flow from the water supply to the system, and a normally closed auxiliary valve to control the flow to a retarding chamber governing the operation of one or more alarm devices.

10 Opening movements of the check valve are effected by excess of pressure in the main as compared with the pressure in the system, and movements of the auxiliary valve are effected solely by those of the check valve.

15 When one or more of the sprinkler heads of the system is opened as by fire or accident, thus providing an outlet for the water in the system, the check valve is forced open by pressure in the main and water then flows through the valve to the opened heads. Under such conditions the auxiliary valve is also unseated, thereby permitting a flow to the retarding chamber, and the alarm is duly given.

25 Because of ever varying pressure in the water main, the check valve is subjected to water hammer and is thereby intermittently unseated to a slight extent. It is of importance that such unseating of the check valve 30 should not cause a false alarm; but it is of even greater importance that any unseating of the valve occasioned by the opening of a sprinkler head should promptly and with certainty operate to sound a true alarm.

35 It is the object of the invention to provide an easily adjustable device, positive and certain in action, wherein intermittent openings of the check valve will not cause false alarms, but even a slight flow occasioned as 40 by fire will be immediately effective to open the auxiliary valve and permit the flow necessary to set the alarm devices in operation.

This object is accomplished as hereinafter set forth, and a preferred manner is shown 45 in the accompanying drawings of a vertical section of the device as a whole,—but it is to be understood that this showing is not to be taken as defining the limits of the invention, reference being had to the appended 50 claims for that purpose.

In the embodiment of the invention as shown, the casing A is provided with the usual inlet passage B communicating with the water supply, and the outlet C communicating with the sprinkler system. The water-

way between the inlet and outlet is controlled by the swinging valve D which seats on the ring E carried by the casing. This valve is hinged to the arm F by the pin G, the arm being carried by the pivot H suitably supported by the casing.

At the outer edge of the valve D, that is at the edge farthest removed from the pivot H, is an extension I to which is attached the auxiliary valve. This latter valve preferably 65 comprises a metal plate J embedded in or otherwise attached to a block K of rubber or other yielding material, the whole being supported by the screw-threaded post L which engages an opening in the extension I and is held in place by the nuts M—M', one on each side of said extension. This valve is normally seated on the bushing N and controls the passage O leading to the alarm devices.

The casing is provided at one side with an 70 opening covered by the plate P secured in position by bolts and nuts Q. Projecting from the inner side of this plate is a stop R against which a projection S on the arm F will abut when the valve is in full open 75 position, as shown in dotted lines. The casing is also provided with an opening, indicated in the drawings by broken lines and directly opposite the auxiliary valve, for the usual pipe connection by which the system 80 above the valve may be drained.

The valve D is hinged to its arm F at a point intermediate the center of the valve and the pivot H. This hinge connection between the valve and its support permits a 90 slight rocking movement of the valve, independent of any movement of the arm, and an accuracy in seating not obtainable by a rigid connection at this point.

The outer edge of the valve D, being 95 farthest removed from the pivot H, will move through a greater arc and with proportionately greater rapidity than the inner edge; and this movement of the outer edge is further accelerated and multiplied by locating the hinge connection between the valve and its arm intermediate the center of the valve and the pivot H, rather than at the center of the valve. By this arrangement, the outer edge of the valve, the portion carrying the extension I, is the first to leave its seat and any subsequent opening movement will be greater at this point than at any other. As a consequence, the auxiliary valve, being at a point still further removed from the 100 105 110 115

fulcrum of the main valve, will describe an arc even greater than the latter, and any movement of the main valve will have an added increment when communicated to the auxiliary valve, causing the latter to open to a greater extent than the main valve itself. This is of importance in the event of only a small flow through the main valve, as with the present arrangement such flow will be confined to the outer portion of the valve; whereas if the main valve were forced from its seat a like distance all around the movement of the auxiliary valve would be only approximately that of the main valve, and such small flow might not open the auxiliary valve sufficiently to effect a filling of the retarding chamber and actuation of the alarm devices.

A yielding or resilient block such as K is preferred as the simplest and most positive form of auxiliary valve, doing away entirely with springs, diaphragms, and the like. This block is so positioned that it is to some extent compressed on its seat when the main valve is seated; and, by virtue of this compression, the occasional slight openings of the main valve as by water hammer do not operate to move the block from its seat and open the passage to the alarm devices. The mounting of the block, as here shown, permits of quick and positive positioning by means of the nuts M—M', which are accessible through the opening in the casing, normally covered by the plate P, so the pressure

25 of the block on the seat N may readily be adjusted to any desired degree in order that the opening of the passage may be either delayed or accelerated, as desired, following the initial opening of the main valve beyond a predetermined extent.

When the main valve is opened more than just sufficient to take up the compression in the block, the auxiliary valve will follow the lead of the former and have a movement in unison therewith,—thus opening the passage to the alarm devices. If such opening of the auxiliary valve is occasioned only by excessive water hammer, and not because of the opening of a sprinkler head, an alarm will nevertheless not be given as the auxiliary valve will be forced back upon its seat, be-

fore the retarding chamber has been sufficiently filled to actuate the alarm.

A further advantage of the block as shown is found in the fact that any slight shifting of the main valve, or change of position on its seat, is fully cared for by such a block when made somewhat larger than its seat.

The outer end of the arm F may be weighted, if desired, in order that greater pressure may be required to unseat the valve D, and so that only slight water hammer would be ineffective to open the auxiliary valve at all. This is more particularly of importance when the valve as a whole is installed in a horizontal position (that is, when the water main is horizontal and the valve D itself is in a vertical position). When the main is in a vertical position and the valve D is horizontal, the weighted arm is of less importance, as the weight of the valve itself with the added weight of the water in the system will ordinarily be sufficient to keep the valve closed.

Any tendency of the main valve to open first at its side nearest the pivot H, due for example to suction on the auxiliary valve exerted through the passage O and the retarding chamber, may be overcome as by boring and threading the lever arm F to receive the screw T, which screw may be turned as desired to regulate the play between the end thereof and the outer face of the valve D. When positioned, the screw is held in place by the lock nut U.

Having thus described the invention, the following is claimed:

In an alarm check valve, a casing, a lever pivoted therein, a main valve, a connection between said lever and said valve at a point intermediate the pivot of the former and the center of the latter, and an auxiliary valve comprising an adjustable stem carried by said main valve and yielding means supported by said stem, said auxiliary valve in operation having initially a delayed opening movement with respect to said main valve and thereafter a movement in unison therewith.

In testimony whereof, I have signed my name to this specification.

LESTER A. GRIMES.
